MULTI-STAGE AXIAL-FLOW COMPRESSORS WITH ADJUSTABLE PITCH STATOR BLADES

Alfred Cyril Lovesey, Littleover, Geoffrey Light Wilde, Coxbench, and David Omri Davies, Edgware, England, assignors to Rolls-Royce Limited, Derby, England, a British company

Application October 13, 1950, Serial No. 189,968

Claims priority, application Great Britain
October 28, 1949.

11 Claims. (Cl. 230—114)

It is usual to design a multi-stage axial-flow compressor so as to obtain efficient operation at a particular speed, or at a particular condition dependent on the speed, and this involves matching of the blades of all the stages of the compressor by suitable selection of the blade characteristics, such as angle of incidence and shape, for example to give a constant axial velocity of the fluid to be compressed at the particular speed or condition dependent on speed.

The angle of incidence at which the rotor blades operate for any given speed of rotation is determined by the axial velocity of the fluid and the direction of swirl given to the fluid by the stator blades.

At speeds below the designed speed, when the pressure rise per stage is less than the designed pressure rise, there will tend to be an accelerating flow from the entry to the exit of the compressor due to the designed over-all density ratio not being achieved. This acceleration appears as a reduction in the axial velocity at the entry and an increase in the axial velocity at the exit.

Where the axial velocity of the fluid is lower than the designed axial velocity, the angle of incidence becomes positive and so high that the blades run in a stalled condition, and where the axial velocity is higher than the designed velocity the blades run at a negative angle of incidence and therefore do not contribute their share to the pressure rise. At speeds above the designed speed, when the pressure rise per stage is greater than the designed pressure rise, there will tend to be a decelerating flow from the entry of the compressor to the exit due to the designed over-all density ratio being exceeded. This deceleration appears as an increase of the axial velocity over the designed velocity at the entry and a decrease at the exit.

Therefore any departure of the operating condition of the axial-flow compressor from the designed speed or from the condition dependent on the speed adversely effects the efficiency of the compressor.

To enable a multi-stage axial-flow compressor to operate with high efficiency over a range of compressor rotational speeds it has been proposed to provide adjustable pitch stator blades, and a multi-stage axial-flow compressor having such an arrangement of stator blades is described and claimed in U. S. Patent No. 2,613,029.

The term "rotational speed" is to be understood as meaning either the actual rotational speed of the engine or the corrected rotational speed. The corrected rotational speed is equal, as is well known in the art, to the actual rotational speed divided by the square root of the absolute temperature at inlet to the engine.

This invention is concerned with multi-stage axial-flow compressors having adjustable-pitch stator blades and has for an object to provide an improved method of controlling the flow conditions in such a compressor so as to maintain a high efficiency of compression through a wide speed range. Another object of the invention is to provide an improved method of and apparatus for controlling the pitch of the stator blades. The term "stator blades" includes inlet whirl vanes for an axial-flow compressor which may in certain cases be followed by another row of stationary blades.

Accordingly this invention consists in one aspect in a method of controlling the flow conditions in a multi-stage axial-flow compressor of kind comprising adjust-

2

able pitch stator blades, which method comprises, over part at least of the range of rotational speeds of the compressor, automatically varying the pitch of the adjustable-pitch stator blades so that for each speed in the range over which control is effected the stator blades have an appropriate pitch. Thus, as the speed of the compressor progressively changes through the range of rotational speeds in which the pitch of the stator blades is varied, the pitch of the blades will be automatically and progressively changed to have at each speed a value appropriate to give efficient operation of the compressor at that speed.

According to this invention in another aspect there is provided the combination with a multi-stage axial-flow compressor having adjustable-pitch stator blades, of means arranged to be operative over part at least of the range of rotational speeds of the compressor automatically and progressively to vary the pitch of the stator blades in a manner corresponding to changes in the compressor rotational speed, so that for each speed the stator blades have a pitch appropriate to give efficient operation of the compressor at that speed.

According to another aspect of the invention, a multi-stage axial-flow compressor having one or more rings of adjustable-pitch stator blades comprises pressure-sensitive means arranged to control the pitch of a ring of the adjustable-pitch stator blades which pressure-sensitive means is arranged to be loaded in one sense by a fluid pressure which is a predetermined function of the compressor rotational speed and in the opposite sense by a force which is a function of the pitch of said stator blades so that for each rotational speed of the compressor, the stator blades have a corresponding pitch.

Some constructional arrangements of this invention as applied in an axial-flow compressor of a gas-turbine engine will not be described with reference to the accompanying drawings in which:

Figure 1 illustrates diagrammatically a gas-turbine engine having an axial-flow compressor with adjustable stator blades;

Figure 2 is a detail section through a construction of operating mechanism for adjusting the adjustable stator blades;

Figure 3 illustrates a modification of the mechanism of Figure 2;

Figure 4 illustrates another construction of operating mechanism for the stator blades; and

Figure 5 illustrates yet another construction of operating mechanism for the stator blades.

Referring to the drawings there is shown a gas-turbine engine (Figure 1) which comprises a multi-stage axial-flow compressor 10, combustion equipment 11, receiving compressed air from the compressor 10, and a turbine 12 receiving combustion products from the combustion equipment 11, and arranged to drive the compressor 10 through a shaft 13.

Fuel is supplied to the combustion equipment 11, to be burnt in the compressed air, by means of a well-known fuel system comprising an engine-driven swash-plate variable-delivery pump 14 (Figures 1 and 2) which comprises a rotor 15 having a number of cylinders or bores formed therein containing plungers 16 which on rotation of the pump rotor 15 are constrained to reciprocate in the cylinders or bores against the action of springs 17 and thereby to draw in fuel from the suction pipe 18 of the pump 14 and to deliver it to the engine through a delivery pipe 19. The pump drive from the engine is indicated at 20 (Figure 1).

The pump rotor is formed with a central bore 21 leading from the suction pipe 18 of the pump to a series of radial drillings 22 which place the central bore 21 in communication with a chamber 23 housing the pump rotor 15. The pump rotor 15 thereby acts as a centrifugal pump and the pressure within the chamber 23 is a function of the engine rotational speed and thus of the rotational speed of the compressor 10.

The multi-stage axial-flow compressor 10 is provided with one or more rings of adjustable stator blades (illustrated as two rings of such blades 24a, 24b) the blades forming each ring of blades being interconnected so as to be capable of simultaneous adjustment.

Conveniently each adjustable blade may be provided with an operating arm 25 engaged in a notched ring 26 rotatable in the stator structure of the compressor to rock the arms 25 of a ring of blades simultaneously.

In order that the compressor may operate efficiently over a wide range of engine speeds, it is desirable that the pitch of the stator blades 24a, 24b should be adjusted so that for each rotational speed of the compressor 10 their pitch is suitable to give a high efficiency of the compressor. It is thus arranged that as the engine rotational speed increases so the pitch of the stator blades 24a, 24b changes proportionally and for this purpose the following control arrangement for the adjustable pitch stator blades may be provided.

One adjustable stator blade of each of the rings of blades 24a, 24b is connected for adjustment with an associated hydraulic ram 30 (Figures 1 and 2) and the hydraulic ram comprises a cylinder 31, an operating piston 32 working within the cylinder 31, and a control mechanism 33 whereby the position of the piston 32 within the cylinder 31 is determined by the engine rotational speed. Since the position of the piston 32 within the cylinder 31 determines the pitch of the associated stator blades 24a, 24b, the pitch of the stator blades 24a, 24b will thus be determined in accordance with the engine rotational speed.

The ram cylinder 31 is provided internally with a pair of bushes 34, 35 engaged by the stem 32a of the piston so that the piston stem is guided in the bushes, and the piston 32 itself is located intermediate the length of the stem 32a and between the bushes 34, 35, so that the bushes act as limit stops for the piston. The stem 32a is hollow and in communication through bore 36 with the cylinder chamber 37 on one side of the piston head. In this way the effective area of the side or end of the piston 32 exposed to chamber 37 is substantially greater than the side or end of the piston 32 exposed to cylinder chamber 38. The cylinder 31 is provided with a pressure fluid supply connection 39, which in this arrangement is connected for convenience to the delivery pipe 19 of the engine-driven swash-plate type variable-delivery pump 14, and bores 40, 41 are taken from this connection 39 to the chambers 37, 38, on each side of the ram piston 32, the bore 40 to the chamber 37 on the side of the piston of larger effective area comprising a flow restrictor 42 the purpose of which will be clear from the following description.

Mounted on the end of the ram cylinder 31 adjacent the side of the piston 32 having the larger effective area, there is provided the control mechanism 33 for the piston 32. This control mechanism comprises a chamber divided into two compartments 43, 44 by a flexible diaphragm 45, the compartment 43 which is nearer the ram cylinder 31 being connected to the suction pipe 18 of the fuel pump 14 through a connection 46 and the compartment 44 being connected by a pipe connection 47 to the chamber 23 of the fuel pump 14 into which pressure fluid is delivered by the centrifugal pump formed by the pump rotor. The flexible diaphragm 45 is thus loaded in one direction (in a direction towards the ram cylinder) by a pressure which is a function of the engine actual rotational speed.

The flexible diaphragm 45 is also arranged to be loaded by a spring 50 accommodated within the hollow stem 32a of the ram piston 32 and for this purpose the end wall of the ram cylinder is formed with an axially-directed neck 51 having therein a bore fitted with a sleeve 52 containing a sliding push rod 53, one end of which bears on an abutment 45a on the diaphragm 45 and the other end of which bears against an abutment member 54 for the spring 55. The other abutment for the spring is formed integrally with the piston stem. The push rod 53 slides in the sleeve 52 and suitable fluid-tight seals, conveniently formed by lands 53a, are provided to prevent leakage of pressure fluid from the ram cylinder 31 into the compartment 43 to the left of the diaphragm 45 as viewed in the drawings. It will be clear that as the piston 32 moves in the ram cylinder 31 towards the control mechanism 33, the load on the diaphragm 45 due to the spring 50 will increase and the load will be dependent upon the position of the piston 32 within the ram cylinder 31. It will also be clear that the spring load will oppose the fluid pressure load on the diaphragm 45.

The flexible diaphragm 45 is also arranged in this construction to be loaded by a secondary spring 55 in the same sense as by the spring 50 accommodated in the stem 32a of the piston 32. The secondary spring 55 has one abutment afforded by the abutment member 45a carried by the diaphragm 45 and its second abutment on a shoulder 56 formed within the neck 51 supporting the sleeve 52 for the push rod 53.

Movements of the flexible diaphragm 45 under control of the fluid pressure and spring loads are communicated to a second push rod 57 mounted slidably in a bush 58 fitted in the wall of the diaphragm compartment 44 and movements of the push rod 57 are in turn communicated to a half-ball carrier 59 forming part of a valve mechanism. This mechanism comprises a half-ball element 62 which co-operates with a bleed port 63 in member 64 to control the flow of pressure fluid from a passage 60, which communicates with the ram cylinder chamber 37, into a chamber 61 housing the valve mechanism. The second push rod 57 is formed with lands 57a co-operating with the wall of the bore of bush 58 to provide a fluid seal between the diaphragm compartment 44 and the chamber 61. This chamber 61 is connected by pipe connection 65 with the suction pipe 18 of the fuel delivery pump 14. The half-ball carrier 59 and the second push rod 57 are lightly loaded by a spring 66 towards engagement with the flexible diaphragm 45.

The operation of the hydraulic ram is as follows.

Assuming that the engine is stationary then the half-ball bleed valve 62 will be closed on its seat around port 63 and the piston 32 will be at the end of the ram cylinder 31 remote from the control mechanism 33 where it is held by the main spring 50. If now the engine is started up the pressure on each side of the ram piston will increase, but since there is no leak from cylinder chamber 37, the piston 32 will remain stationary. At the same time, the fluid pressure in pump chamber 23 and thus the fluid pressure acting on the diaphragm 45 will increase due to increase in engine speed.

When the fluid pressure acting on the diaphragm 45 has increased sufficiently to overcome the secondary spring 55 and thereby to permit the half-ball bleed valve 62 to open, pressure fluid bleeds off from the ram cylinder chamber 37 on the side of the piston having the greater effective area and the pressure within the cylinder on this side of the piston head will fall due to the presence of the flow restriction 42 in its feed bore 40. When the pressure on this side of the cylinder falls sufficiently, the resultant pressure load on the piston 32 will overcome the spring 50 and the piston 32 will start to move within the cylinder 31 and will continue to move so long as the engine rotation speed increases until the piston head 32 abuts against the limit stop formed by bush 35.

It will be seen that the secondary spring 55 acts to afford a lower limit to the range of speeds over which the ram 30 is effective to adjust the pitch of the stator blades 24a, 24b.

Assuming now that the engine speed is steady within the range of speed over which the ram 30 operates to adjust the pitch of the stator blades 24a, 24b and that the engine speed is increased to a new speed in this range, then the pressure acting on the diaphragm 45 will be increased permitting the half-ball bleed valve 62 to open and to bleed off fluid through passage 60 from ram cylinder chamber 37 communicating with the side of the piston 32 of larger effective area. The pressure on this side of the piston 32 therefore falls (due to the presence of flow restriction 42 in its feed bore 40) and the piston 32 moves to the right as seen in the drawing within the ram cylinder 31, gradually increasing the spring load afforded by the main spring 50 on the diaphragm 45, thus tending to close the half-ball bleed valve 62 and to cut down the bleed flow from the ram cylinder chamber 37. When the piston 32 reaches a position in the cylinder appropriate to the new engine speed, the half-ball bleed valve 62 will have been closed off to such an extent that the pressure within the cylinder space 37 communicating through passage 60 with the bleed valve 62 has such a value that the loads acting on the piston 32 are balanced and the piston will stabilise in this position. In this position moreover the spring load on the diaphragm 45 will balance the fluid pressure load derived from chamber 23 due to the pressure from the pump rotor.

From the foregoing description, it will be seen that for each engine actual rotational speed, the piston 32 occupies a corresponding position in the ram cylinder 31 so that the pitch of the stator blades 24a, 24b controlled by the hydraulic ram 30 can be arranged to be that appropriate to the particular engine speed; moreover for progressive changes of speed the pitch of the stator blades will be adjusted progressively.

If it is desired to control the pitch of the stator blades to be a function of corrected engine speed (i. e. actual speed divided by the square root of the engine intake temperature), the flexible diaphragm 45 need not be loaded by the pressure fluid delivered by the centrifugal pump formed in the fuel pump rotor as above described, but may be loaded by an arrangement such as is shown in Figure 3. In this arrangement, a pipe 70 is provided with its ends connected to the suction pipe 18 and there is arranged in the pipe 70 a fixed-capacity positive-displacement pump 74 which is driven at a speed proportional to engine speed, and, hydraulically in series therewith, a restricting orifice device 71 whereof the effective area is controlled by a valve element 72 carried by an expansible capsule 73 arranged to expand and contract in response to variations in the engine intake temperature. The pipe connection 47 from the compartment 44 of the diaphragm chamber of the ram control mechanism 33 is connected to the pipe 70 between the orifice 71 and the delivery of pump 74 and the pipe connection 46 from the compartment 43 on the other side of the diaphragm 45 is connected to pipe 70 downstream of the orifice 71 so that the diaphragm 45 is loaded by the pressure drop across orifice 71.

The fuel flow through the orifice 71 is proportional to engine speed, and if the effective area of the orifice 71 is controlled by capsule 73 to be proportional to the square root of the engine inlet temperature, the pressure drop across orifice 71 and thus the pressure difference applied across the diaphragm 45 is proportional to the corrected rotational speed (that is the actual engine rotational speed divided by the square root of the inlet temperature).

The capsule 73 is illustrated as being connected internally by capillary 75 to a bulb 76 located in the engine intake (see also Figure 1) and the bulb 76, capillary 75 and capsule 73 are all filled with fluid so that the capsule 75 expands and contracts with the fluid filling on sensing by the bulb 76 of increases or decreases of the air temperature in the engine intake. The ram 30 is supplied with pressure fluid for its operation as in Figure 2 by being connected through the supply connection 39 to the delivery pipe 19 of the main fuel pump 14.

In a further constructional arrangement illustrated in Figure 4 of a ram device 30 suitable for use in accordance with the invention, a control force is obtained which is proportional to the square of the rotational speed, and opposing force is obtained which is proportional to the engine inlet temperature, and these forces are suitably combined to provide a resultant force approximately proportional to the engine corrected speed. In this arrangement the compartment 43 of the chamber containing the diaphragm 45 is connected to the suction side of the fuel pump 14 as in the arrangement of Figure 2 and the other compartment 44 is connected as in Figure 2 to the chamber 23 of the fuel pump 14 into which pressure fluid is delivered by the centrifugal pump formed in the pump rotor.

There is provided in the compartment 43 nearer the ram cylinder 31 an arrangement of capsules to give the desired control force dependent on the inlet air temperature.

The push rod 53, of which one end bears on the diaphragm 45 and the other end bears against the abutment member 54 for the compression spring 50 of the ram piston, is provided with a radially extending disc-like part 80. Between said disc-like part 80 and the wall of the compartment 43 nearer the ram cylinder 31, there is arranged a capsule 81, the interior of which communicates by means of the capillary tube 75 with a temperature-sensitive bulb element 76 in the engine air intake. The interior of the capsule 81, the capillary 75 and the bulb element 76 are filled with a fluid which expands on increase in temperature, in a known manner. The capsule 81 is normally in contact with the disc-like part 80 and the wall of the compartment 43. Between the disc-like part 80 and flange-like abutment 82 which projects

radially inwardly from the wall of the compartment 43 between the diaphragm and the disc-like part, there is located an evacuated capsule 83. This capsule 83 is normally in contact with the disc-like part 80 and with the abutment 82. The flange-like abutment 82 is so arranged that the full area of the diaphragm 45 is still subjected to the pressure in the compartment 43 which is connected as in Figure 2 to the inlet of the fuel pump 14. The diaphragm 45 is also subjected to the load of a spring 84 on the side thereof remote from the ram cylinder 31, the spring 84 abutting the member 45a carried by the diaphragm 45 and the wall of compartment 44 remote from the ram cylinder 31. This spring 84 serves to counteract the resilient load exerted by the capsules 81, 83. In all other respects this constructional arrangement is similar to that described above with reference to Figure 2.

In operation, the diaphragm 45 is loaded in the sense of opening the half-ball valve 62 by the pressure fluid from the pump chamber 23. This control load is, therefore, proportional to the square of the engine rotational speed. The opposing load is produced as follows: an increase in the temperature of the air at the inlet of the engine causes the fluid in the parts 76, 75, 81 to expand and causes a load to be supplied to the push-rod 53 in the sense of closing the half-ball valve 62, and to move the diaphragm against the spring 84 which abuts it. This load is arranged to be proportional to the temperature of the air at the inlet of the engine. It will be appreciated that the provision of the evacuated capsule 83 on the side of the disc remote from the fluid-filled capsule 81 ensures, by correct selection of the relative areas of the two capsules 81, 83, that the load applied to the disc 80 is independent of the fuel pump inlet pressure in the compartment 43.

To produce a control force approximately proportional to engine corrected speed in such a system, the dimensions of the capsules 81, 83 and of the diaphragm 45 are so arranged that, at one selected value of the corrected speed, the stator blades 24a, 24b will have one unique setting, irrespective of the actual temperature. In this way, it may be arranged that any error which is introduced as the corrected speed departs from this selected value, the error being dependent on the intake temperature and on the relation of the stator blade pitch to the selected pitch, will be negligible over the range of control required in practice.

In another constructional arrangement of ram device, a further modified form of temperature control is provided. In this case (Figure 5) the half-ball valve 62 is carried on one end of a lever 90 which rocks on a pivot formed by a flexible diaphragm 91 separating chamber 44 from chamber 61. The portion of the lever 90 on the side of the diaphragm 91 remote from the half-ball valve 62 is connected by a tappet element 93 to the flexible diaphragm 45, so that movement of the diaphragm 45 in a direction away from the ram cylinder 31 tends to allow the half-ball valve 62 to close. There is also provided a spring 94 serving to urge the half-ball valve towards the closed position. The spring 94 is accommodated in a chamber 95 and is arranged to bear through a push-rod 96 on the end of the lever 90 adjacent to the half-ball valve 62. The end of the spring 94 remote from the half-ball valve is arranged to abut a second push-rod 97 which is loaded by means of a capsule 173 which has its interior connected by capillary tube 75 to a temperature-sensitive element such as the element 76 in the engine air intake, and which capsule 173 is arranged to expand on increase of temperature. A load proportional to temperature is thereby applied to the half-ball valve 62 in a sense of tending to close the half-ball valve 62, the load increasing on increase of temperature and being applied by means of the capsule 173 through the spring 94. In other respects this arrangement is similar to the second arrangement described.

It will be seen that in this arrangement the half-ball valve is loaded through diaphragm 45 in the sense of opening by a force, due to the pressure fluid of the centrifugal pump of the engine fuel pump, proportional to the square of engine speed, and in the opposed sense by a force proportional to the inlet temperature of the engine.

By suitable selection of the areas of the diaphragm 45 and of the capsule 173, and of the moment arms of the lever 90, a control force may be produced on the bleed

valve 62, as in the second arrangement described, approximately proportional to engine corrected speed.

In this construction, no secondary spring such as the spring 55, is provided for pre-loading the diaphragm 45, but the spring 94 can be arranged to have the same effect as the spring 55.

We claim:

1. A multi-stage axial-flow compressor having at least one ring of adjustable-pitch stator blades connected for simultaneous adjustment, power means operatively connected to said blades for adjusting the pitch of said blades, pressure-sensitive means, means to produce a fluid pressure which is a predetermined function of the compressor rotational speed and to apply said fluid pressure to the pressure-sensitive means to load it in one sense, and means to load said pressure-sensitive means in the opposite sense with a load which is a function of the pitch of the adjustable pitch stator blades, said pressure-sensitive means being operatively connected to said power means for adjustment of said power means when the balance of the loads to which said pressure-sensitive means is subjected is upset, said adjustment being in the sense to restore said balance, whereby for each rotational speed of the compressor the stator blades have a corresponding pitch.

2. A multi-stage axial-flow compressor as claimed in claim 1, wherein said power means comprises a hydraulic ram having a cylinder and a piston, said piston having ends provided with effective areas of different size, connecting means between said piston and said stator blades for adjusting simultaneously the pitch of the stator blades of a ring of adjustable stator blades, a fluid pressure source, pressure connections from said source to said ram to load both ends of said piston, said pressure-sensitive means controlling the fluid pressure on the end of the piston of larger effective area to have a value relative to the fluid pressure on the smaller area end of the piston to balance the loads on the piston, whereby for each rotational speed in the range of rotational speeds of the compressor the ram piston occupies a corresponding position in the ram cylinder.

3. A multi-stage axial-flow compressor having at least one ring of adjustable-pitch stator blades, the blades of said ring being connected for simultaneous adjustment; a hydraulic ram including a cylinder, and a piston in said cylinder dividing said cylinder into first and second pressure spaces and connected with the stator blades of said ring to adjust the pitch of said blades progressively on progressive movement of said piston in said cylinder, said piston having its side which is open to the first pressure space of less effective area than its side open to the second pressure space; a pressure fluid source; a first supply connection leading from said pressure fluid source to said first pressure space and being in continuous communication therewith; a second supply connection from said pressure fluid source to said second pressure space; a flow restrictor in said second supply connection; a bleed conduit connected with said second pressure space; a bleed valve controlling the outlet of said bleed conduit; spring means arranged to load said bleed valve towards the closed position; means to vary the load exerted by said spring means on said bleed valve in dependence on the position of said piston in said cylinder; a second pressure fluid source having a fluid pressure which is a function of the compressor rotational speed; and a pressure-responsive device connected to be subjected to the fluid pressure of said second pressure fluid source and connected to said spring means to oppose the load exerted thereby.

4. A multi-stage axial-flow compressor as claimed in claim 3, comprising also a second spring means arranged to apply a preselected substantially constant load to the pressure-responsive device in the sense of closing the bleed valve, thereby to determine the lower limit of compressor rotational speed at which adjustment of the stator blade pitch is effected.

5. A multi-stage axial-flow compressor as claimed in claim 4, having a first abutment for one end of said second spring means, the opposite end of said second spring means being in abutment on the pressure-sensitive device.

6. A multi-stage axial-flow compressor as claimed in claim 3, comprising as said second pressure fluid source a centrifugal pump driven at a speed proportional to the compression rotational speed and connected to said pressure-sensitive device to load the pressure-responsive device as a function of the actual compressor rotational speed.

7. An arrangement as claimed in claim 6, having the centrifugal pump formed in the rotor of a swashplate variable delivery pump forming part of an engine fuel system.

8. A multi-stage axial-flow compressor as claimed in claim 3, comprising as said second pressure fluid supply source fixed-capacity positive-displacement pump arranged to be driven at a speed proportional to the compressor rotational speed, a delivery conduit from said pump, a flow-restricting orifice arranged in said conduit to restrict flow therethrough, and pressure connections from said conduit on each side of said flow-restricting orifice to corresponding sides of said pressure-responsive device.

9. A multi-stage axial-flow compressor as claimed in claim 8, comprising also temperature-responsive means arranged to respond to the temperature at the inlet of the compressor and to vary the effective area of said flow-restricting orifice to be proportional to the square root of the temperature at the inlet to the compressor.

10. A multi-stage axial-flow compressor as claimed in claim 3, having said second pressure fluid supply source arranged to apply to said pressure-responsive device a control force which is proportional to the square of the compressor rotational speed, and comprising also means responsive to the temperature at the inlet to the compressor and arranged to load said pressure-responsive device in a direction opposite to said control force with a force which is proportional to said temperature, said pressure-responsive device and temperature-sensitive means being so arranged that at one selected value of the corrected speed of the compressor the ram piston will occupy a given setting irrespective of the value of said temperature.

11. A multi-stage axial-flow compressor as claimed in claim 3, comprising also temperature-sensitive means arranged at the intake of the compressor, and arranged to load said bleed valve in a sense of closure with a load which is dependent on the temperature at the intake to the compressor, and having said second pressure fluid supply source arranged to load the pressure-responsive device with a load proportional to the square of the compressor rotational speed, said temperature-sensitive means and said pressure-responsive device being so arranged that the control force acting on the bleed valve is approximately proportional to the compressor corrected speed.
